US00D727868S

(12) **United States Design Patent**
O'Neill et al.

(10) **Patent No.:** **US D727,868 S**
(45) **Date of Patent:** **** Apr. 28, 2015**

(54) **OPTICAL COMPONENT**

(71) Applicant: **olloclip, LLC**, Huntington Beach, CA
(US)

(72) Inventors: **Patrick D. O'Neill**, Huntington Beach, CA (US); **Chong Pak**, Lakewood, CA (US)

(73) Assignee: **olloclip, LLC**, Huntingdon Beach, CA (US)

(**) Term: **14 Years**

(21) Appl. No.: **29/473,454**

(22) Filed: **Nov. 21, 2013**

(51) **LOC (10) Cl.** **16-06**

(52) **U.S. Cl.**

USPC **D14/134**

(58) **Field of Classification Search**

CPC **G02B 7/02**

USPC **D16/134, 130, 208; D14/432, 433, 251, D14/240, 358; 359/824, 827, 544, 811; 455/90.3, 575.1, 569.1, 567**

(57) **CLAIM**

The ornamental design for an optical component, as shown and described.

DESCRIPTION

FIG. 1 is a front, top, right side perspective view of an optical component;

FIG. 2 is a back, bottom, and left side perspective view thereof;

FIG. 3 is a right side elevation view thereof;

FIG. 4 is a left side elevation view thereof;

FIG. 5 is a front side elevation view thereof;

FIG. 6 is a back side elevation view thereof;

FIG. 7 is a top plan view thereof;

FIG. 8 is a bottom plan view thereof;

FIG. 9 is a front, top, and right side perspective view of another embodiment of an optical component;

FIG. 10 is a back, bottom, and left side perspective view thereof;

FIG. 11 is a right side elevation view thereof;

FIG. 12 is a left side elevation view thereof;

FIG. 13 is a front side elevation view thereof;

FIG. 14 is a back side elevation view thereof;

FIG. 15 is a top plan view thereof; and,

FIG. 16 is a bottom plan view thereof.

The features illustrated in phantom line form no part of the claimed design.

1 Claim, 16 Drawing Sheets
